Atty:

UNITED STATES PATENT OFFICE.

WILLIAM L. WEINTZ, OF OTTAWA, ILLINOIS, ASSIGNOR TO J. E. PORTER CORPORATION, OF OTTAWA, ILLINOIS, A CORPORATION OF ILLINOIS.

FARROWING RAIL.

Application filed September 5, 1922. Serial No. 586,077.

To all whom it may concern:

Be it known that I, WILLIAM L. WEINTZ, a citizen of the United States, residing at Ottawa, in the county of La Salle and State 5 of Illinois, have invented new and useful Improvements in Farrowing Rails, of which the following is a specification.

This invention relates to farrowing rails for hog pens.

One object of my invention is to provide a positive lock for the rail requiring that it be moved endwise in one direction to unlock it, thus preventing the rail from being unlocked by the animal in the pen rubbing 10 against it or pushing up on the rail when lowered or pulling down on it when raised.

A further object of my invention is to make the lock automatic in its action, that is to cause the locking to take place immediately the rail reaches the position to which it is swung.

A further object of my invention is to have the supports for the rail engage and embrace the bottom bar of the pen and several of the upright filler bars or pickets in order to provide a rigid and strong support for the rail and prevent bending of the parts.

The invention consists further in matters 25 hereinafter described and more particularly set forth in the appended claims.

In the accompanying drawings—

Fig. 1 is a side view of a pen wall looking at the same from the inside thereof and 30 showing pivoted thereto a farrowing rail of my invention;

Fig. 2 is an enlarged vertical sectional view, with parts in elevation, taken on line 2-2 of Fig. 1 and showing the farrowing 35 rail raised in dotted lines;

Fig. 3 is a top plan view taken on line 3-3 of Fig. 2;

Fig. 4 is a side view of one of the parts 40 of one of the rail supporting castings; and

Fig. 5 is a view of a detail of construction showing one of the locking pins released from one of the sockets provided in the part 45 shown in Fig. 4.

Figs. 6 and 7 show the manner in which 50 the rail is attached to wood and concrete or like walls, respectively.

In Fig. 1 of the drawings, I have shown one of the walls of a hog pen. As illustrated, said wall comprises upper and lower

bars 1 and 2 horizontally arranged and vertically spaced apart by upright filler bars or pickets 3, 3 extending between and connected with said bars 1, 2 as in wall constructions of this general kind.

Located inside of the pen wall thus described is a farrowing rail 4. This has pivoted or hinged connection with said wall at the bottom bar 2 by two fittings or castings 5, 5 constructed in accordance with my invention. Both fittings being alike, a description of one will suffice for both.

As shown in Figs. 2 and 3, a fitting 5 is made in two separable parts or sections 6, 7. These are made substantially semicircular in shape to fit about the bottom bar 2 and are provided above and below with lugs or ears 8, 9, respectively to receive bolts 10, 10 for clamping the sections 6, 7 to and about the bottom bar 2. Said sections 6, 7 are also made to fit about and embrace the adjacent upright filler bar or picket 3 and to accomplish that said sections are provided with substantially semicircular upright sections 11, 12. The lugs 8, 9 are on opposite side of these upright sections 11, 12 and the bolts 10 engaging the same serve to clamp the upright sections about and embrace the filler bar or picket as shown in Figs. 1 and 2.

By the construction described, the fittings 5, 5 not only engage and embrace the bottom bar 2 but also engage and embrace the adjacent upright filler bars or pickets 3, thereby providing a rigid and strong support for the farrowing rail 4. This holds the parts against bending when the animal in the pen places its entire weight on the rail.

The inner section 7 of each casting 5 is provided with a vertically arranged inwardly extending web 13. This is preferably made integral with the section 7 and is provided with a bolt hole 14 and two sockets or recesses 15, 16 as shown in Fig. 4. These sockets 15, 16 open through the same side 95 of the web 13 and are on opposite sides of the bolt hole 14, one above and the other below said bolt hole 14, as shown in said Fig. 4. To support the farrowing rail 4 from the webs 13 of the castings 5, 5 there are provided two bracket arms 17, 17, both clamped at their outer ends to the rail 4 by bolts 17. These arms are arranged oppo-

site the castings 5, 5 so that there is one arm for each casting.

The inner end of each arm 17 is bifurcated as shown in Fig. 3, to provide a space 5 for the adjacent web 13. This positions the members 18, 19 at the bifurcated end of the arm 17 on opposite sides of the web 13 and all of such parts are connected by a pivot bolt 20 which hinges the arm 17 to the web 10 13. By the structure described, the farrowing rail 4 has hinged connection with the pen wall and may be swung from the lowered position shown in full lines in Figs. 1 to 3 to the raised position shown in the 15 dotted lines in Fig. 2.

To positively lock and hold the farrowing rail 4 in either lowered or raised position, I provide on the member 18 of each arm 17 an inwardly projecting locking pin 20 21 adapted to enter either of the recesses 15, 16 in the adjacent web 13. To releasably hold said pin in said recesses, I provide a spring 22 coiled about the pivot bolt 20 and located between the web 13 and the other 25 member 19 of said arm. Said spring seats in a recess 23 in said member 19, as in Figs. 3 and 5. The space between the members 18, 19 is wider than the width of the web 13, thus allowing the pin 21 to be released from 30 either of the sockets 15, 16 by moving the rail 4 endwise in a direction to draw the pin out of the engaged socket, as shown in Fig. 5. When so moved, the member 18 is pulled away from the web 13 and the other member 19 toward it as shown in said Fig. 5.

To limit the downward swing of the rail 4, I provide the member 18 of each bracket arm 17 with a stop lug 24 to engage beneath a stop shoulder 25 on inner section 12 of the 40 adjacent casting 5 as clearly illustrated in Fig. 2. This relieves the pivot pins 20 of the weight of the animal when on the rail 4.

To unlock the rail and swing it either upward or downward, as may be required, the 45 rail 4 is first moved endwise to release the pins 21 from their engaged sockets (15, 16), whereupon the rail 4 is swung in the direction required. During this movement the pins ride against the webs 13 between the 50 sockets 15, 16 and that holds the springs 22, 22 compressed. As soon as the pins reach the sockets (15, 16) toward which they are moved, the springs 22 expand and snap the pins into such sockets at the same time moving the rail 4 endwise and effecting a positive lock of the rail in that position. This locking action is automatic and takes effect 55 immediately the parts reach the proper portion without requiring the workman to do more than swing the rail into the position desired. Making it necessary to move the rail 4 endwise to unlock it prevents the animal in the pen from unlocking the rail by moving against it. Moreover, the lock 60 being by pins 21, prevents the animal raising

the rail when down by pushing upon it, or swinging it down when raised by pulling down on the same.

For attaching the rail 4 to either a wood or concrete wall, I employ the form of 70 bracket shown in Figs. 6 and 7. As there shown the web 13 is integral with a flat plate 26 arranged in the plane of said web, or substantially so, and is provided with a plurality of holes 27, 27, arranged about a 75 larger hole 28. When attaching to a wood wall, post or studding 29, I use bolts 30 through the holes 27, as shown in Fig. 6. When attaching to a concrete or tile wall 31, the plate 26 is embedded in the wall and 80 portions thereof extend through and fill the holes 27, 28 as shown in Fig. 7.

While I have shown and described herein in detail, a farrowing rail embodying the features of my invention, it is of course to 85 be understood that the details of construction and arrangement of parts may be variously changed, and modified without departing from the spirit and scope of my invention.

I claim as my invention:

1. The combination with a pen wall, of a farrowing rail, means providing pivotal connection for said rail with said wall to permit raising and lowering of said rail, and means for locking said rail in either raised or lowered position and being released upon moving said rail endwise in one direction.

2. The combination with a pen wall, of a farrowing rail, means adjacent the ends of said rail for pivotally connecting the same with said wall to permit raising and lowering of said rail, and means at said pivotal connections for locking the rail in either raised or lowered position and being simultaneously released upon moving said rail endwise in one direction.

3. The combination with a pen wall, of a farrowing rail, means adjacent the ends of said rail for pivotally connecting the same with said wall to permit raising and lowering of said rail, and means at said pivotal connections for locking the rail in either raised or lowered position, said locking means acting automatically to lock the rail in either of said positions immediately the rail reaches the same and being released upon moving said rail endwise in one direction.

4. The combination with a pen wall, of a farrowing rail, means adjacent the ends of said rail for pivotally connecting the same with said wall to permit raising and lowering of said rail, means for locking said rail in either raised or lowered position comprising associated parts on the pen wall and rail, one of said parts having sockets to receive locking pins on the other, and spring means acting to snap the pins in said sockets

when brought opposite same, said spring means acting to releasably hold the said pins in their sockets and permitting withdrawal of the pins therefrom to unlock the 5 rail by moving the latter endwise against said spring means.

5. The combination of a pen wall having upper and lower bars connected by interposed upright filler bars, of a farrowing 10 rail adjacent the lower bar and arranged substantially parallel thereto, castings adjacent the ends of said rail and engaging and embracing both the lower bar and the adjacent filler bars, arms secured to the 15 said rail opposite said castings and having pivotal connection therewith to permit raising and lowering of said rail, and coacting means on said castings and arms for locking the said rail in either raised or lowered 20 position.

6. The combination with a pen wall having upper and lower bars connected by interposed upright filler bars, of a farrowing rail adjacent said lower bar and arranged 25 substantially parallel thereto, castings adjacent the ends of said rail and each being made of two separable sections shaped to fit about and embrace both the lower bar and the adjacent filler bar, means for clamping 30 the sections about said bars, the inner sections of said castings having inwardly extending webs, arms secured to said rail at said castings and extending toward the same, said arms having their inner ends 35 pivoted to said webs, and locking means carried by said arms and webs for locking said rail in either raised or lowered position, said locking means acting to automatically lock said rail in either of said 40 positions immediately the rail reaches the same.

7. The combination with a pen wall having top and bottom bars connected by interposed upright filler bars, of a farrowing rail adjacent the bottom bar and arranged 45 substantially parallel thereto, castings adjacent the ends of said rail and each being made of two separable sections shaped to fit about and embrace the bottom bar and the adjacent filler bar, means for clamping said 50 castings about said bars, the inner sections of said castings having inwardly extending webs, arms secured to said rail opposite said castings and having their inner ends bifurcated to receive said webs, pivot pins

connecting said arms with said webs, locking pins on said arms to enter sockets in said webs, thereby being sockets on opposite sides of said pivot pins to lock the rail in either raised or lowered position, coil springs about said pivot pins to releasably hold said pins in said sockets and permit the withdrawal of the pins therefrom by moving said rail endwise in a direction against said springs. 55

8. The combination with a pen wall having top and bottom bars connected by interposed filler bars, of a farrowing rail adjacent the bottom bar and arranged substantially parallel thereto, castings adjacent the ends of said rail and each being 60 made of two separable sections shaped to fit about and embrace the bottom bar and adjacent filler bar, the inner sections of said castings having inwardly extending webs, arms secured to said rail opposite said castings and having their inner ends bifurcated to receive said webs, pivot pins connecting the bifurcated ends of said arms to said webs, locking pins on one of the bifurcated parts of said arms to enter sockets in said webs, said sockets being arranged on opposite sides of said pivot pins for locking said rail in either raised or lowered positions, and coil springs about said pivot pins between said webs and the other of the bifurcated parts of said arms for releasably holding the pins in said sockets, the last named parts having recesses to receive said springs. 65

9. The combination with a pen wall of a farrowing rail, arms carried by said rail and pivoted to fixed parts on said wall, a stop member on said fixed part to be engaged by lug on said arm to limit the downward swing of said rail, and co-acting 90 means on said arms and fixed parts for locking said rail in either raised or lowered position, said locking means acting automatically to lock said rail in either of said 95 positions immediately the rail reaches the same and being released upon moving said rail endwise in one direction. 100

In testimony that I claim the foregoing as my invention, I affix my signature this 30th day of August, A. D. 1921. 105

WILLIAM L. WEINTZ.
